UNITED STATES PATENT OFFICE.

GEORGE H. BABCOCK, OF PLAINFIELD, NEW JERSEY.

DESIGN FOR A ROOFING-TILE.

SPECIFICATION forming part of Design No. 20,405, dated December 16, 1890.

Application filed May 14, 1890. Serial No. 351,813. Term of patent 14 years.

To all whom it may concern:

Be it known that I, GEORGE H. BABCOCK, a citizen of the United States, residing at Plainfield, in the county of Union and State of New Jersey, have invented and produced a new and original Design for Roofing or Sheathing Tiles, of which the following is a specification, reference being had to the accompanying drawing, forming a part thereof.

10 The design relates to a clay or other roofing or sheathing tile having substantially a flat exposed surface, which, when assembled with other tiles of like surface, forms a laterally-continuous surface; and said design consists in the contour or shape of the tile, in its surface 15 ornamentation, and in its contour or shape, combined with the surface ornamentation.

15 The accompanying illustration illustrates a face view of a tile of the new design.

20 The design relates particularly to the exposed or lower face of a tile, its upper portion partaking of various shapes.

25 As illustrated, the tile A has diagonal upper sides, which bear upper flanges. The lower or exposed portion of the tile is pro-

vided with two straight sides, each terminating in a spur *g*, that merges into the lower side, which is straight for a short distance, and then is formed with a deep central spur *g* of spade-like form. The surface ornamentation of the exposed face of the tile consists in a Cherokee rose *D*, arranged in conventional form, having a center bead *e*, with radiating petals *d*, slightly overlapping one another and formed by curved lines *f*, which terminate by reversed curves *f'* in a point. In the petals *d* are radiating lobes arranged substantially in the center of the petals.

30 It may be stated that when a number of such tiles are assembled the lower sides of the 35 continuous tiles form a connected series of deep and short spurs, as indicated by the dotted lines.

It may be stated that when a number of such tiles are assembled the lower sides of the 40 continuous tiles form a connected series of deep and short spurs, as indicated by the dotted lines.

What is claimed is—

45 The design for a tile, substantially as described and shown.

GEO. H. BABCOCK.
